HEATING DEVICE

Thomas E. Turner, Mounds, Okla.

Application August 12, 1940, Serial No. 352,197

5 Claims. (Cl. 257—212)

This invention relates to heating devices and more particularly to heating devices for tanks designed to store oil whereby the oil may be conditioned to effect settling out of water and so-called "bottom settling" without the use of chemicals and/or steam as is ordinarily the practice, and in such a manner that the oil is maintained at a temperature suitable for ready passage of the oil into flow lines from the storage tank; the principal objects of the present invention being to provide a convenient, relatively economical and highly efficient heating device of the character noted; and to provide improved elements and arrangements of such elements in a heating device of the character and for the purpose noted.

In accomplishing these and other objects of the present invention, I have provided improved details of structure, the preferred form of which is illustrated in the accompanying drawings, wherein:

Figure 1 is a perspective view of a tank equipped with a heating device embodying the features of the present invention, parts of the device being broken away to better illustrate its construction.

Figure 2 is a vertical cross section through the tank and heating device illustrated in Figure 1.

Figure 3 is a top plan view of the tank and heating device shown in Figure 1.

Figure 4 is a horizontal cross section through the tank and heating device substantially on the line 4—4, Figure 2.

Figure 5 is a plan view of the tank support and foundation illustrated in Figure 2.

Figure 6 is a detail horizontal cross section substantially on the line 6—6, Figure 1, particularly illustrating the adjustable and demountable nature of the shell.

Referring more in detail to the drawings:

1 generally designates a heating device embodying the features of the present invention which is preferably employed in connection with and for heating the contents of a tank 2.

In oil producing practice, it is customary to pump oil and other fluids from wells periodically and to store such fluids until such time as it is desired to sell or use the fluids. In cold weather the fluids, and particularly oil, become thick and sluggish and do not flow freely. Water and undesirable sediments also are carried in the thick oil. As above indicated, it is desirable, in accordance with this invention, to heat the oil to facilitate settling out of water and undesirable constituents from the oil to the bottom of the tank containing such fluids.

To this end, the tank 2 which may be of suit-

able size and construction, is mounted on a spider 3, Figure 5, which preferably includes arms 4 that radiate from a central support 5 and terminate in overlying relation to a base 6 of concrete or the like that is set in the ground 7. The base 6 is dished to provide a sump 8, the sump being provided with a drain 9 to carry off oil in case the tank 2 should leak or overflow, and to thus obviate the danger of fires or explosions. 10 The sump 8 is also provided with a heated air inlet duct 10 which conducts air into the sump from a point or points exteriorly of the sump. Air in the duct 10 is heated by a furnace 11 that is preferably suitably insulated and arranged a suitable distance from the tank for further obviating the danger of fire and explosions.

Mounted on the base 6 preferably at the upper edge thereof and in upstanding surrounding relation to the tank 2 is a layer of insulation 12, 20 the insulation being arranged in spaced relation to the tank 2 to provide an air space 13 between the tank and insulation.

In order to support the insulation 12 a preferably sectional shell, or jacket 14 is provided, which preferably consists of metal or like sheets 15, the side and end edges of which are preferably turned outwardly to provide flanges 16, 17, 18 and 19. The lower end flanges of the sheets are preferably secured as by fastening devices 21 to the upper edge of the base 6. The side flanges of the sheets are preferably secured together, as by fastening devices 22, Figure 4, and the upper end flanges of the sheets are secured, as by fastening devices 23, to a ring-like plate 24 that is horizontally arranged substantially in a plane coincident with the upper edges of the jacket plates, the insulation and the side walls 25 of the tank 2. The tank walls 25 also preferably have outwardly turned edges to form flanges, the lower tank wall flanges being secured as by fastening devices 26 to a bottom wall formed by a plate 27 that rests in supported relation on the spider 3. The upper tank side wall flanges are secured, as at 27, to a top wall 28 for the tank and to the inner periphery of the ring plate 24.

The sides and bottom of the tank 2 are thus enclosed by the insulated jacket and base in such a manner as to provide air spaces below and around the tank, the radial arms 4 of the spider 50 directing heated air admitted to the sump through the duct 10 throughout the whole area of the bottom wall 27 of the tank and over all the area of the side walls of the tank to effectively accomplish heating of the contents of the tank and, 55 where such contents are oil, water and bottom

settlings, to effectively accomplish settling out of the water and settlings from the oil.

In order to regulate the heat within the insulated jacket about the tank, the ring plate 24 is provided with tubes 30 preferably of a number equal to the radial tank supporting arms and further preferably arranged between such arms, as shown in Figure 3. The tubes 30 preferably open downwardly at their outer ends into the heated air space 13 and allow exit of heated air under control of dampers 31, the heated air passing through the tubes 30 into a centrally arranged stack 32 as by the inlet openings 33 therein, the heated air subsequently passing off into atmosphere or to other points for suitable disposition.

It is desirable to control the amount of heat to be applied to the oil or other contents of the tank 2 in order to economize on fuel and in order further to properly condition the oil. A thermostat control 35, Figure 2, is, therefore, preferably mounted in a side wall of the tank, which control is adapted to act through a line 36 extending from the side walls of the tank through the side walls of the jacket to a thermostat 37, Figure 1, of a construction suitable for operating a valve 38 in a fuel supply line 39 leading to the furnace 11.

A suitable inlet 41 and a suitable outlet 42 for the tank 2 are also preferably provided to supply the tank with fluids from a well and to allow flow of conditioned oil from the tank. A suitable drain 43 for water and bottom settlings is also provided for the tank.

The operation of a heating device constructed as described is as follows:

Well fluids are applied to the tank 2 through the inlet 41 to a suitable level in the tank. It is known that temperature affects the condition of the oil, and that higher temperatures cause the oil to flow freely while lower temperatures cause the oil to congeal into a relatively thick mass. As explained above, it has heretofore been the practice to treat the oil with chemicals and/or apply steam to the oil in order to effect a separation of undesirable constituents entrained in the oil. In the present instance the furnace 11 is actuated to cause heated air to flow through the duct 10 into the sump 8 of the base 6 below the tank, the radial arm supports directing such heated air throughout the sump below the tank and up around the side walls of the tank between the outwardly spaced insulated heated air jacket and the tank. The heated air thus substantially surrounds the tank and heats the oil therein to facilitate separation of the undesirable constituents of the oil, which settle downwardly on to the bottom wall of the tank. Excesses of heated air pass through the tubes 30 under control of the dampers 31 and pass into the stack 32 where they are suitably disposed of. When the temperature of the oil reaches a predetermined degree that is suitable for this purpose, and in order to conserve fuel and avoid unnecessary waste thereof, the thermostatic control 35 acts on the thermostat 37 in such a manner as to actuate the valve 38 and limit passage of fuel through the line 39 to the furnace 11 in quantities sufficient to supply only the necessary amounts of heated air to the sump 8 below and the heated air space around the tank 2.

Due to the arrangement of furnace, the jacket, the tubes and the stack, relative to the tank 2 and base 6, it is apparent that should it be desired to move those elements of the present heating device from one tank to another, the heat-

ing device may be readily disassembled and moved to another desired location, it being further apparent that sections or sheets of the jacket may be added to or subtracted from the number provided for one tank and that the jacket may thus be adjusted to a size desired for another tank at another location. Another advantage in this arrangement is that should it be desired to move the tank 2 to another location, the heating device may be readily moved along with the tank either in assembled or disassembled relation to the tank to such other location.

It is apparent, therefore, that I have provided a convenient, relatively economical and highly efficient heating device of the character and for the purpose above noted.

What I claim and desire to secure by Letters Patent is:

1. In an apparatus of the character described, a tank, a base supporting the tank and having a housing arranged below the bottom wall of the tank, a spider in the housing, means for introducing a heating medium to the housing near the center of the spider for heating the contents of the tank, and means adjacent the confines of the housing and having communication therewith for exhausting heating medium therefrom, said spider having arms radiating approximately from the center of the bottom wall of the tank to the confines of the housing on said base for directly supporting the tank and for directing heat across the bottom of said tank.
2. In an apparatus of the character described, a tank, a jacket surrounding the tank and spaced from the sides and bottom wall of the tank, a spider in the space between the jacket and the bottom wall of the tank, and means for introducing a heating medium to the jacket near the center of the spider for heating the contents of the tank, said spider having arms radiating approximately from the center of the bottom wall of the tank for directly supporting the tank and for directing heat across the bottom of said tank.
3. In an apparatus of the character described, a tank, a base supporting the tank and having a housing arranged below the bottom wall of the tank, a jacket surrounding the tank and spaced therefrom, the jacket communicating with said housing, a spider in the housing, and means for introducing a heating medium to the housing under and near the center of the spider for heating the contents of the tank, said spider having arms radiating approximately from the center of the bottom wall of the tank to the confines of the housing on said base for directly supporting the tank and for directing heat across the bottom of said tank.
4. In an apparatus of the character described, a tank, a base supporting the tank and having a housing arranged below the bottom of the tank, a jacket surrounding the tank and spaced therefrom, the jacket communicating with said housing, a spider in the housing, means for introducing a heating medium to the housing under and near the center of the spider for heating the contents of the tank, said spider having arms radiating approximately from the center of the bottom wall of the tank to the confines of the housing on said base for directly supporting the tank and for directing heat across the bottom of said tank.
5. In an apparatus of the character described, a tank, a base supporting the tank and having a jacket surrounding the tank and spaced therefrom, the jacket communicating with the housing, a spider in the housing, and means for selectively controlling passage of heating medium through said tubes for regulat-

ing the direction of passage of the heating medium through the jacket.

5. In an apparatus of the character described, a tank, a base having a housing arranged below the bottom wall of the tank and having outer confines spaced from the side walls of the tank, a jacket mounted on the base and having communication therewith, said jacket being formed of sections having outwardly directed flanges, insulating means secured to the inner surface sections, fastening means securing the jacket sections together in surrounding and insulating relation to the side walls of said tank in spaced relation thereto, a spider in the housing, means

for introducing a heating medium to the housing under and near the center of the spider for heating the contents of the tank, said spider having arms radiating approximately from the center of the bottom wall of the tank to the confines of the housing of said base for directly supporting the tank and for directing heat across the bottom of said tank, tubes leading from the jacket for exhausting heating medium from the jacket, and means for selectively controlling passage of heating medium through said tubes for regulating the direction of the passage of the heating medium through the jacket.

THOMAS E. TURNER.
